UNITED STATES PATENT OFFICE.

JOSEPH A. C. ROBERTSON, OF TORONTO, ONTARIO, CANADA.

PNEUMATIC HAMMER.

Application filed April 17, 1924. Serial No. 707,239.

To all whom it may concern:

Be it known that I, JOSEPH A. C. ROBERTSON, of the city of Toronto, in the county of York, Province of Ontario, Canada, a subject of the King of Great Britain, have invented certain new and useful Improvements in Pneumatic Hammers, of which the following is a specification.

This invention relates to pneumatic hammers adapted to automatically feed a nail into position under the hammer and to drive it home, and my object is to provide a device of this character which is of simple construction and cheap to manufacture, yet durable and efficient.

I attain my objects by means of the constructions hereinafter described and illustrated in the accompanying drawings in which—

20 Fig. 1 is a longitudinal section of my improved hammer;

Fig. 2 a front elevation of the same;

Fig. 3 a view similar to Fig. 1, showing the parts in different positions and partly 25 broken away;

Fig. 4 a cross section of the cylinder;

Fig. 5 a vertical section on the line 5—5 of Fig. 4;

Fig. 6 a diagrammatic view showing the 30 construction employed to cause the hammer to be reciprocated;

Fig. 7 a cross section of the nail feeding device;

Fig. 8 a horizontal section of the same;

35 Fig. 9 a plan view of the hopper;

Fig. 10 a plan view of the underside of the plunger tube; and

Fig. 11 a plan view of the underside of the base.

40 In the drawings like numerals of reference indicate corresponding parts in the different figures.

1 is a cylinder having exhaust and inlet ports 2 and 3, the latter communicates with 45 a valve controlled fluid supply pipe 4 carried by the cylinder head 5 connected to the cylinder. A handle 6 is also formed on or connected with the head. In the cylinder is slidably and rotatably mounted a hammer or piston 7 having a pair of inlet passages 8 and 8^a and a pair of exhaust passages 9 and 9^a formed therein. The inlet passage 8 is adapted to register with the inlet port 3 to direct the fluid to the top of 50 the cylinder and at the same time the exhaust passage 9 is adapted to register with

the exhaust port 2 to exhaust the air below the cylinder and thus cause the piston to be moved downwardly in the cylinder, see Figs. 1 and 4. The other set of passages 8^a and 9^a 60 are adapted to register with the inlet and outlet ports 3 and 2 to cause the piston to be moved upwardly in the cylinder and therefore the passage 8^a communicates with the space below the piston and the passage 9^a 65 communicates with the space above the piston, see Fig. 3.

To cause these two sets of passages 8 and 9, 8^a and 9^a to alternately register with the inlet and exhaust ports respectively, 70 and thus automatically cause the piston to be reciprocated, the piston at the end of each stroke is partially rotated alternately in opposite directions in the following manner.

Stationary members 10 and 11 are suitably secured at opposite ends of the cylinder, the member 10 being located at one side 75

of the cylinder and having its lower face inclined in one direction. The member 11 is located at the opposite side of the cylinder and has its upper face inclined in the opposite direction to the inclined face of the member 10. These members are fitted in recesses formed in the wall of the cylinder and project into the bore thereof. The 80 piston is provided with inclined shoulders 12 and 13 adapted to engage the inclined faces of the members 10 and 11 respectively. These shoulders are formed by forming recesses 12^a and 13^a in the periphery of the 85 piston, the shoulder 12 being inclined in the same direction as the inclined face of the member 10 and is also of greater width than the latter. With this arrangement as the piston moves upwardly, with the passages 8^a and 9^a in register with the ports 3 and 2 respectively, see Fig. 3, the shoulder 12 engages the member 10 and rides up the inclined face of the latter which causes the 90 piston to be rotated sufficiently to cut off 100 the said communications and bring the passages 8 and 9 into register with the ports 3 and 2 respectively. The fluid is then directed to the space above the piston which forces the latter downwardly and causes 105 the shoulder 13 to engage the inclined face of the member 11. This shoulder is inclined in the same direction as the inclined face of the last mentioned member and is of greater width than the latter whereby the piston is partially rotated in the opposite direction to that caused by the engagement of the 110

shoulder 12 and the member 10. The communications between the passages 8 and 9 and the ports 3 and 2 are thus cut off and the passages 8^a and 9^a are registered with the said ports respectively and the piston is moved upwardly in the cylinder as hereinbefore described. It will readily be seen that with the above construction the piston will be constantly reciprocated when the valve in the fluid supply pipe 4 is open.

Referring to Fig. 4, it will be noted that the recesses 12^a and 13^a are of greater depth than the thickness of the members 10 and 11 which provides a space adapted to catch any foreign substance to prevent the latter resting on the inclined faces.

The hammer or piston 7 is adapted to actuate a nail set or plunger 14, which is axially movable in a tube 15, removably carried by the cylinder 1. The tube is slidably mounted on a tubular base 16 adapted to rest on or against the object, through which the nail is to be driven. On the base is suitably carried a feed chamber 17 which communicates with the bore thereof and carries a magazine comprising a hopper 18 and intermediate magazine sections 17^a. The sections and the hopper have a telescopic connection with one another and with the feed chamber so that they may be easily and quickly separated from one another or from the feed chamber. The magazine sections are of curved tubular shape so that by removing one or both of them the hopper may be positioned relative to the feed chamber 17 so that the nails in the hopper will feed by gravity into the feed chamber when the device is used in a horizontal position. The lower end of the hopper is reduced in width so that only one nail at a time can drop into the magazine sections 17^a and the feed chamber 17.

Referring to Figs. 1, 3 and 5, it will be noted that the plunger 14 is provided with an integral collar 19 adapted to engage an annular shoulder 20 formed in the tube 15 which limits the downward movement of the plunger to prevent it falling through the device when the latter is lifted off the part being nailed. To limit the upward movement of the plunger relative to the tube, the collar 19 is adapted to engage a bushing 21 carried in the bottom portion of the cylinder 1. The upper end of the plunger passes through this bushing, which is removable, so that it may be easily replaced when worn, as it is important that no fluid leakage should occur at this point. The lower end of the plunger is slidably mounted in the bore of the base 16 whereby the plunger, the tube 15, and the cylinder 1 may be moved axially of the base to cause a nail to be driven home or to permit these parts to be positioned so that a nail may be fed into the bore of the base as hereinafter described.

The lower end of the tube 15 is slotted at 22 to provide clearance for the feed chamber 17, see Fig. 10. To position this slot relative to the feed chamber and to limit the upward movement of the tube 15 relative to the base 16, a pin and slot connection 23 is provided in these parts. To limit the downward movement of the tube 15 relative to the base, the latter is provided with a shoulder 16^a adapted to engage the bottom of the said tube.

To automatically feed a nail into the bore of the base 16, when the plunger 14 is raised, I provide a pair of feeders 24 formed of disks having peripheral teeth cut therein (see Figs. 7 and 8) and adapted to be actuated as follows. The feeders operate through slots formed in the chamber 17 and are secured, with their teeth in vertical alinement, to opposite ends of a tube 25 journalled on an actuating rod 26 which is journalled in a pair of brackets 27 secured to the feed chamber 17. A disk 28 secured to the actuating rod has a dog 29 pivotally connected thereto which is adapted to pick a ratchet wheel 30 secured to one of the feeders 24. The actuating rod has a laterally extending arm 26^a formed on or secured thereto, which arm is normally held, by means of a spring 31, in engagement with the outer surface of the tube 15 as indicated in full lines in Fig. 8. The lower end of this tube is provided with a cam 32 adapted to engage the arm 26^a, when the handle 6 and thus the tube 15 is raised, to swing it sufficiently to cause the ratchet wheel and thus the feeders to be rotated one tooth forward. This movement causes a nail, which has been fed by gravity from the hopper 18 into the feed chamber 17, to be forced laterally, by the alined teeth *a* of the feeders, see Fig. 8, through the feed chamber 17 and into the bore of the base 16 where it drops by gravity. This same movement causes the teeth *b* of the feeders to engage and single out the first nail from the column of nails lying in the chamber 17 and move it forward so that on the next partial rotation of the feeders it will be fed forward into the bore of the base 16.

To prevent lateral movement of the lower ends of the nails in the chambers, and to prevent the nails striking the base and bouncing back into the chamber I provide the lower end of the hopper, the chambers 17 and 17^a and the communication between the chamber 17 and the base 16 with a channel 33 (see Figs. 1 and 7) of greater width than the remainder of these parts and adapted to receive the heads of the nails. As the nail is forced forward by the feeders 24 it drops into the tubular base 16 as hereinbefore described, but as the lower end of the communication between the bore of the latter and the chamber 17 is of less width than the width of the channel, the head of the nail

prevents lateral movement of the nail within the bore of the base.

The nail is positioned in axial alinement with the plunger 14 by means of its head engaging the bore of the base 16 and its point engaging a centering groove 34 formed in each of a pair of fingers 35. These fingers are pivotally mounted on lugs formed on the lower end of the base 16 and have their lower ends projecting through a slot formed in the lower end of the base (see Fig. 11). Springs 36 of any suitable shape are adapted to engage the base and the upper ends of the fingers to normally hold the lower ends of the latter in contact with one another and thus centrally position the grooves 34. When the nail receives its first blow, the springs permit the fingers to slightly separate to permit the passage of the stem of the nail between them.

To swing the lower ends of the fingers 35 clear of the head of the nail, the lower end of the tube 15 is provided with oppositely directed extensions having inclined faces 36 formed therein adapted to engage the upper ends of the fingers and squeeze them towards one another (see Fig. 10).

To permit the use of various lengths of spikes or nails having the same sized heads, the hopper is provided with a plurality of sets of grooves 37 and 37^a. Each set of these grooves is adapted to receive and position a false bottom (not shown) for the hopper so that the heads of the nails will be positioned for entry into the channel 33.

As hereinbefore mentioned, the tube 15 is removably carried by the cylinder 1, a set screw 38 being provided to hold these parts together, the purpose of this arrangement is to enable the same cylinder and hammer to be used with various sized plungers and bases 16 which have to be substantially the same size as the head of the nail to obtain the best results.

Assuming nails have been placed in the hopper and the lower end of the base 16 set against the board to be nailed, the mode of operation is as follows. The handle 6 is raised to the position shown in Fig. 1, which causes the actuating rod 26 to be functioned by the cam 32 to move the feeders to single out the forward nail in the feed chamber and position it so that when the actuating rod is again actuated by the cam 32 the nail will be forced into the bore of the base 16 and a second nail will be singled out and positioned for feeding when the handle 6 is again raised to its upper position. This does not occur until the first nail is driven home, and it will be understood that only the first nail requires two movements of the rod 26 to position it for engagement with the plunger 14. The handle 6 is then lowered until the plunger engages the head of the nail, the cylinder 1 being supported by the

bushing 21 resting on the collar 19 formed on the plunger, see Figs. 3 and 5. It will be noted that when the plunger is in this position and the hammer 7 is located at the top of the cylinder, a space is left between the hammer and the plunger or nail set 14 so that the former will have sufficient momentum to strike the latter, when the fluid valve is opened, and thus force the nail a certain distance into the board on each downward stroke of the hammer. After each blow of the hammer is imparted to the nail, the plunger rests on the head thereof and the tube 15 is slid farther down on the base 16. This tube is assisted in its downward movement by means of the fluid pressure on the bottom of the cylinder when the hammer is being returned to the top of the cylinder. When the lower end of the tube gets near the shoulder 16^a, the fingers 35 are engaged by the inclined faces 36 and squeezed together to permit the head of the nail to pass between them. When the nail is driven home, the fluid valve is manually closed and the handle 6 raised to its upper position, which causes the cam 32 to actuate the rod 26 to cause a partial rotation of the feeders 24 to feed the second nail into the bore of the base 16 and at the same time to single out the third nail and position it for feeding.

When the device is used for driving large nails or spikes, a foot rest 39, suitably carried on the lower end of the tube 15, enables the operator to hold the device to its work. The foot rest is adapted to be thrown back out of the way or removed when not required. It will be understood that, while the terms nail and nail-set have been used throughout the specification, the device may be used for riveting or any other purpose to which it is suited.

What I claim is:

1. In a device of the class described the combination of a base having a passage therein; a fluid pressure means including a cylinder slidably mounted on the base; a hammer adapted to drive a nail; means for feeding one nail at a time into the base passage; a pair of fingers pivoted at the lower end of the base and normally adapted to contact with one another to center the point of the nail; and means carried on the lower end of the cylinder to open the said fingers to permit the passage of the nail head therebetween.

2. In a device of the class described the combination of a base having a passage therein; fluid pressure means including a cylinder slidably mounted on the base; a hammer adapted to drive a nail; means for feeding one nail at a time into the base passage; a pair of fingers pivoted on the lower end of the base and provided with a centering groove adapted to receive the point of a

- 5 nail, the base being provided with a slot to receive the said fingers; springs adapted to normally hold the fingers in contact with one another to center the point of the nail; and means carried on the lower end of the cylinder to open the said fingers to permit the passage of the nail head therebetween.
3. In a device of the class described the combination of a base having a passage 10 therein; fluid pressure means including a cylinder slidably mounted on the base; a hammer adapted to drive a nail; means for feeding one nail at a time into the base passage; a pair of fingers pivoted intermediate 15 their ends adjacent the lower end of the base and provided with centering grooves adapted to receive the point of a nail, the base being provided with a slot to receive the said fingers; springs adapted to engage 20 the upper ends of the fingers to normally hold the lower ends thereof in contact with one another to center the said nail point; and means carried on the lower end of the cylinder for engaging the upper ends of the 25 said fingers to spread apart the lower ends thereof to permit the head of the nail to pass through the end of the base passage.
4. In a device of the class described the combination of a base having a passage 30 therethrough; a chamber carried by the base communicating with the passage thereof; fluid pressure means adapted to drive a nail including a cylinder slidably on the said base; means for feeding one nail at a time 35 from the chamber into the base passage; ratchet means for operating the said feeding means; an actuating rod for operating the said ratchet means; and a cam carried by the said cylinder and adapted to engage 40 the actuating rod to operate the feeding means, when the cylinder is raised to position the fluid pressure means for engagement with a fresh nail.
5. In a device of the class described the 45 combination of a base having a passage therethrough; a chamber carried by the base communicating with the passage thereof; fluid pressure means adapted to drive a nail including a cylinder; a tube detachably 50 connected with the cylinder and slidably mounted on the base, the tube having a slot adapted to provide clearance for the chamber and provided with a cam; a pair of rotatable feeders adapted to engage a nail in 55 the chamber; a ratchet wheel secured to one of the feeders; a dog adapted to pick the ratchet wheel; and an actuating rod adapted to operate the dog and normally held in engagement with the outer surface of the tube 60 and adapted to be engaged by the said cam to cause the nail to be forced from the chamber into the base passage.
6. In a device of the class described the 65 combination of a tubular base; a chamber carried by the base and communicating with the bore thereof; fluid pressure means adapted to drive a nail including a cylinder; an axially alined tube detachably connected therewith and slidably mounted on the tubular base, the tube having a slot adapted to 70 provide clearance for the chamber, a pin and slot connection between the tube and the base for positioning the slot relative to the chamber and for limiting the upward movement of the tube relative to the base; and means for feeding one nail at a time from the chamber into the bore of the base.
7. In a device of the class described the 75 combination of a tubular base; a chamber carried by the base and communicating with the bore thereof; fluid pressure means adapted to drive a nail including a cylinder; an axially alined tube detachably connected therewith and slidably mounted on the tubular base, the tube having a slot adapted to 80 provide clearance for the chamber; a pin and slot connection between the tube and the base for positioning the slot relative to the chamber and for limiting the upward movement of the tube relative to the base; means for feeding one nail at a time from the chamber into the bore of the base; and means for automatically actuating the feeding means, when the fluid pressure means is raised to 85 position it for engagement with a fresh nail.
8. In a device of the class described the 90 combination of a tubular base; a chamber carried by the said base and communicating with the bore thereof; fluid pressure means adapted to drive a nail including a cylinder having an axially alined tube detachably connected therewith, the tube being slidably mounted on the tubular base and being slotted to provide clearance for the chamber; and a pin and slot connection between the tube and the base for positioning the slot relative to the chamber and for limiting the upward movement of the tube relative to 95 the base.
9. In a device of the class described the 100 combination of a tubular base; a chamber carried by the said base and communicating with the bore thereof; fluid pressure means adapted to drive a nail including a cylinder having an axially alined tube detachably connected therewith, the tube being slidably mounted on the tubular base and being slotted to provide clearance for the chamber and provided with a cam at its lower 105 end; a pin and slot connection between the tube and the base for positioning the slot relative to the chamber and for limiting the upward movement of the tube relative to the base; means for feeding one nail at a time from the chamber into the base bore; and means for actuating the feeding means operable by the said cam.
10. In a device of the class described the 110 combination of a tubular base; a chamber carried by the said base and communicating with the bore thereof; fluid pressure means adapted to drive a nail including a cylinder having an axially alined tube detachably connected therewith, the tube being slidably mounted on the tubular base and being slotted to provide clearance for the chamber and provided with a cam at its lower 115 end; a pin and slot connection between the tube and the base for positioning the slot relative to the chamber and for limiting the upward movement of the tube relative to the base; means for feeding one nail at a time from the chamber into the base bore; and means for actuating the feeding means operable by the said cam.
11. In a device of the class described the 120 combination of a tubular base; a chamber carried by the said base and communicating with the bore thereof; fluid pressure means adapted to drive a nail including a cylinder having an axially alined tube detachably connected therewith, the tube being slidably mounted on the tubular base and being slotted to provide clearance for the chamber and provided with a cam at its lower 125 end; a pin and slot connection between the tube and the base for positioning the slot relative to the chamber and for limiting the upward movement of the tube relative to the base; means for feeding one nail at a time from the chamber into the base bore; and means for actuating the feeding means operable by the said cam.
12. In a device of the class described the 130 combination of a tubular base; a chamber carried by the said base and communicating with the bore thereof; fluid pressure means adapted to drive a nail including a cylinder having an axially alined tube detachably connected therewith, the tube being slidably mounted on the tubular base and being slotted to provide clearance for the chamber and provided with a cam at its lower end; a pin and slot connection between the tube and the base for positioning the slot relative to the chamber and for limiting the upward movement of the tube relative to the base; means for feeding one nail at a time from the chamber into the base bore; and means for actuating the feeding means operable by the said cam.

- with the bore thereof; fluid pressure means adapted to drive a nail including a cylinder having an axially alined tube detachably connected therewith, the tube being slidably mounted on the tubular base and being slotted to provide clearance for the chamber and provided with a cam at its lower end; a pin and slot connection between the tube and the base for positioning the slot relative to the chamber and for limiting the upward movement of the tube relative to the base; means for feeding one nail at a time from the chamber into the base bore; means for actuating the feeding means operable by the said cam; fingers adapted to engage the point of a nail to center it in the bore of the base; and means carried by the lower end of the tube for spreading the fingers apart to permit the passage of the nail head between them.
11. The combination of a base having a passage therethrough; a tube slidably mounted on the base; a nail set slidably mounted in the said passage; movable fingers carried on the base and adapted to center the point of a nail lying in the base passage; and releasing means carried on the tube for spreading the fingers apart, the tube being adapted to follow the driven movement of
- the nail set whereby the releasing means will actuate the fingers to provide clearance for the nail head.
12. The combination of a base having a passage therethrough; a tube slidably mounted on the base; a nail set slidably mounted in the said passage; fingers pivoted intermediate their ends on the base and having their lower ends adapted to contact with one another to centrally locate the point of a nail; and releasing means carried on the tube adapted to engage the upper ends of the said fingers to spread their lower ends apart, the tube being adapted to follow the driven movement of the nail set whereby the releasing means will actuate the fingers to provide clearance for the nail head.
13. In a device of the class described the combination of a base; a feed chamber connected therewith; a magazine comprising detachably connected curved tubular sections; and a hopper adapted to be detachably connected with the outer end of any one of the sections to enable the device to be used at various angles to its work.

Signed at Toronto, Canada, this 29th day of March, 1924.

JOSEPH A. C. ROBERTSON.
